US00D920297S

(12) **United States Design Patent** (10) **Patent No.:** **US D920,297 S**
(45) **Date of Patent:** **** May 25, 2021**

(54) **RFID LABELS**

(71) Applicant: **AVERY DENNISON RETAIL INFORMATION SERVICES, LLC**, Mentor, OH (US)

(72) Inventors: **Ian Forster**, Chelmsford (GB); **Michael Lake**, Pawe Paw, MI (US); **Brad Cumby**, Liberty Township, OH (US)

(73) Assignee: **Avery Dennison Retail Information Services, LLC**, Mentor, OH (US)

(**) Term: **15 Years**

(21) Appl. No.: **29/685,898**

(22) Filed: **Apr. 1, 2019**

(51) LOC (13) Cl. **14-03**

(52) U.S. Cl.

USPC **D14/230; D20/22**

(58) **Field of Classification Search**

USPC D14/138, 230-238, 299, 358; D12/42, D12/43; D20/22

CPC H01Q 7/00; H01Q 13/10; H01Q 9/285; H01Q 19/30; H01Q 19/12; H01Q 1/38; H01Q 1/36; H01Q 2/0027; H01Q 1/48; H01Q 9/045; H01Q 1/243; H04B 1/0475; H04B 1/034; H05K 11/00
